PACKAGING TRAY

Henry R. Vigue, 18 Pleasant St., Waterville, Maine

Filed Dec. 30, 1964, Ser. No. 83,547

Term of patent 14 years

(Cl. D58—13)

Fig. 5.

Fig. 6.

Fig. 8.

Fig. 7.

Fig. 9.

Fig. 10.

Fig. 11.

Fig. 12.

FIG. 1 is a top plan view of a packaging tray embodying my new design wherein the upper rim of the tray sidewall is elevated at the opposite ends of the packaging tray, the ends in plan view are curvilinear in appearance and the bottom is rounded somewhat along the length of the packaging tray thus causing the bottom portion of each depression to merge with the tray bottom approximately along the longitudinal centerline of the tray;

FIG. 2 is a side elevational view of the packaging tray of FIG. 1;

FIG. 3 is an end elevation view of the packaging tray of FIG. 1;

FIG. 4 is a transverse sectional elevational view of the packaging tray taken on line 4—4 of FIG. 2;

FIG. 5 is a top plan view of a modified form of a packaging tray embodying my new design wherein the upper rim of the tray sidewall lies in a substantially flat plane, the ends are characterized by straight portions, and the bottom is flattened somewhat along the length of the packaging tray thus causing the bottom portion of each depression to merge with the tray bottom laterally remote from the longitudinal centerline of the tray;

FIG. 6 is a side elevational view of the packaging tray of FIG. 5;

FIG. 7 is an end elevational view of the packaging tray of FIG. 5;

FIG. 8 is a transverse sectional elevational view of the packaging tray taken on line 8—8 of FIG. 6;

FIG. 9 is a top plan view of another modified form of a packaging tray embodying my new design wherein the upper rim of the tray sidewall is elevated fully around the opposite ends of the packaging tray, the ends in plan view are curvilinear in appearance, and the bottom is flattened somewhat along the length of the packaging tray thus causing the bottom portion of each depression to merge with the tray bottom laterally remote from the longitudinal centerline of the tray;

FIG. 10 is a side elevational view of the packaging tray of FIG. 9;

FIG. 11 is an end elevational view of the packaging tray of FIG. 9; and

FIG. 12 is a transverse sectional elevational view of the packaging tray taken on line 12—12 of FIG. 10.

The characteristic feature of my new design resides in the combination, in packaging trays of the configuration illustrated, of a substantially elongated tray rendered dish-shaped in lateral cross-section by upwardly and outwardly curving sidewalls of relatively low height and having an upper rim, a plurality of downwardly contoured depressions integrally formed at spaced intervals along the length of the tray symmetrically on opposite sides of the longitudinal centerline of the tray, each depression including a transversely oriented bottom portion all occupying a common substantially flat plane, and each depression including relatively steep sidewalls connecting the bottom portion with the tray sidewalls along opposite sides of the tray.

This is a continuation-in-part of copending application Serial No. D. 78,021 filed January 2, 1964, now abandoned.

I claim:

The ornamental design for a packaging tray, as shown and described.
